UNITED STATES PATENT OFFICE.

ERNEST W. HOLMES, OF CHATTANOOGA, TENNESSEE, ASSIGNOR TO ERNEST HOLMES COMPANY, OF CHATTANOOGA, TENNESSEE, A CORPORATION OF TENNESSEE.

LIFTING JACK.

Application filed September 23, 1924. Serial No. 739,380.

To all whom it may concern:

Be it known that I, ERNEST W. HOLMES, a citizen of the United States, residing at Chattanooga, in the county of Hamilton and State of Tennessee, have invented new and useful Improvements in Lifting Jacks, of which the following is a specification.

This invention relates to lifting jacks for automobiles and proposes the construction of a jack characterized by simplicity of operation and efficiency in action.

The principal object of the invention is the provision of means for enabling the jack automatically to perform its reverse or load-lowering function for any of various lengths of stroke of the jack handle, through a single manipulative movement of the hand, by the wielder of the jack handle, the position of the hand acquired by said movement being maintained throughout the load-lowering operation.

This is in contra-distinction to the usual mode of operation of variable-stroke jacks, in which a "milking" action of the hands must be resorted to at the end of each stroke to reverse the positions of the lifting and holding pawls.

Other objects of the invention will be disclosed as the description of the illustrative embodiment of the invention develops.

In the drawings:—

Figures 1^a, 1^b and 1^c represent a side elevation of my improved jack, partly in section.

Figures 2^a, 2^b and 2^c represent a plan view of the jack also partly in section.

Figure 3 is a side elevation of the reversing cam, several positions of the setting mechanism being indicated.

Figure 4 is a section taken along the line 4—4 of Figure 1^b.

Figure 5 is a transverse section taken along the line 5—5 of Figure 1^a.

Figure 6 is a side elevation of the jack showing the handle in folded position and indicating another position of the handle in dotted lines.

Referring now in detail to the several figures, the numeral 1 represents the main frame of the jack, said frame preferably consisting of an integral bent member having the side members 2 and the end portion 3.

The side members 2 extend forwardly to the point indicated at 4 in Figure 2^b. The main frame is supported upon the vehicle 55 wheels 5 and 6, the latter being carried upon an axle 7 which passes through suitable apertures in the side members 2 adjacent the end member, the axle being rigidly clamped against said end member by means of a U-bolt 8 which passes around said axle and through suitable apertures in said end member. The vehicle wheels preferably rotate upon roller bearings 9. The side members 2 of the main frame are bridged adjacent 60 their forward ends by means of the brace plate 10, the latter being flanged at the sides as shown at 11, the flanged portions being bolted or otherwise rigidly secured to said side members. The brace plate 10 is preferably formed on its under face with a cylindrical boss 12, said boss fitting within a cup 13, the latter constituting part of the 65 caster 14 and being pivotally secured to said brace plate centrally of the boss 12 by means 70 of the pin 15. The boss 12 and cup 13 together form a race-way in which the anti-friction rollers 16 are retained. The vehicle wheels 5 and 6 being independently mounted upon the axle have a differential 75 movement so that the jack may be freely rotated about a vertical axis passing through some point in the axle, the caster 14 arranging itself so that its plane of rotation lies perpendicular to the radius of rotation of 80 the jack.

The forward ends of the side members 2 are perforated for the reception of a pin 17 upon which the portions of the jack mechanism presently to be described are 85 mounted and which affords pivotal connection for the jack handle or lever 18. A spring 39 surrounds the pin 17 and engages the main frame and the jack handle, the function of said spring being to normally 90 maintain the jack handle in an angular position approaching the vertical, said position being indicated by dotted lines in Figure 1^b. The jack handle comprises the side members 19 shown in Figure 1^c which are preferably brought together as shown at 20 where they are connected to the transverse handle bar 21. The main lifting member of the jack, which will hereinafter be 95 100

referred to as the canti-lever, consists of a substantially U-shaped member 22 lying within the main frame and having its free ends pivotally supported by the main frame 5 by means of the pin 23 which passes through the side members of said main frame at an intermediate point. A spacing sleeve 24 may be provided, surrounding the middle portion of said pin and keeping the legs of 10 said canti-lever separated and in close proximity to the side members of the main frame.

The canti-lever is raised by a wedge 25 which re-acts upon bearings carried by said 15 main frame and canti-lever, between which said wedge is adapted to pass. These bearings are carried at points on said canti-lever and main frame intermediate the outer ends of said members and their pivotal connection. In order to avoid weakening the side members of the main frame by undue perforations, said side members are fitted with saddle plates 26 which preferably consist of spaced side walls joined by a top wall, 20 forming a deep channel through which the side frame members extend. Said saddle plates may be of any convenient shape but are here shown as triangular and riveted to the main frame at points 27 and 28 adjacent 25 to two of the vertices thereof. The saddle plates extend below the side members of the main frame and are perforated to receive the roller bearings 29. A shaft 30 passes through said bearings, upon which is 30 mounted the roller 31, said roller being of sufficient length to occupy substantially the full width of space between said side members, affording lateral support to said side members. The canti-lever 22 is provided 35 above said bearings with a similar set of roller bearings 32 in which is journalled a shaft 33 carrying the roller 34. The latter roller is of sufficient width to fit between the legs of the canti-lever. The wedge 25 rests 40 upon the roller 31 and raises the roller 34, and with it the canti-lever. Said wedge is of trapezoidal cross section, the bottom face thereof being as wide as the lower roller and the top face being equal in width to 45 that of the upper roller. The rearward or broad end of the wedge is curved upwardly at the bottom so that it will ride over any uneven places in the garage floor, when the jack is moved in a backward direction. The 50 nose or apex of the wedge is secured in any suitable manner to a rod 35 which passes forwardly over the pin 23 and the spacing sleeve 24 and is connected at its forward end 55 to a flexible section or chain 37 the latter being secured at its opposite end to a ratchet drum 38, best shown in Figures 1^b and 2^b.

The ratchet drum 38 is preferably freely mounted upon the pin 17 and is provided on one side with a flange or lug 40 and on 60 the other with a ratchet wheel 41. A pin

42 bridges the space between said flange and ratchet wheel, being suitably secured to the web of the latter. The end link of the chain 37 is journalled upon said pin. The wedge 25 is advanced between the rollers 31 and 70 34 by a pull imparted to the rod 35 through the chain 37 when the latter is wound upon the drum 38 by rotation of the ratchet wheel 41. Said ratchet wheel is operated by means of the jack handle 18 in the usual manner, 75 said jack handle being provided with a lifting pawl 43 which co-acts with the abrupt shoulders of the ratchet teeth 44 on the downward stroke of the jack handle, and rides over the sloping faces of said ratchet teeth upon the upward stroke of the jack handle. The ratchet wheel 41 is retained in any position by means of the holding pawl 45. Lifting and holding pawls for a 80 ratchet wheel in jack construction are well known but the present lifting and holding pawls, and the controls therefor are of novel and peculiar construction as will presently appear.

There is nothing notable in the manipulation of the jack handle in performing the lifting operation. The jack handle is forcibly depressed, the lifting pawl carrying the ratchet wheel around for a certain fraction of a revolution, the load being transferred 90 to the holding pawl and the latter preventing reverse movement of the ratchet wheel when the handle is raised preparatory to the performance of another lifting stroke. That which is new, and which constitutes 95 the most important feature of the present invention is the novel means called into operation for the performance of the load lowering function of the jack.

Jacks of a type having a definite length 100 of stroke have long been known, in which means is provided for reversing the position of the pawls when changing from the lifting to the lowering function of the jack. But the trend of inventive effort in the evolution of recent jacks has been to devise a 105 jack having available a number of lengths of stroke which may be undertaken in various positions of the jack handle so as to meet the numerous requirements and exigencies incident to modern garage service. In jacks of this type the problem has presented 110 itself of constructing practical means for reversing the pawls to perform the lowering operation for any one of the various lengths of stroke. Up to the present time such means have been exemplified by separate devices on or adjacent to the handle of the jack for independently releasing the pawls, which, devices must be separately manipulated at the end of each stroke in a manner 115 which can be learned only by much practice and which is referred to in garage parlance as "milking the jack." The present invention 120 seeks to simplify the reversing means 125 130

for jacks of the variable stroke type through the operation of instrumentalities of which the following are an example.

The lifting pawl 43 forms part of a casting which includes the sleeve 46 mounted upon the transverse member 47, the latter lying between the side members 19 of the jack handle and being provided with trunnions 48 rotating within bearings in said side members. The bore within the sleeve 46 extends radially with respect to the axis of rotation of the member 47. The casting is also formed with an arm 49 terminating in an eye 50. A U-bolt 51 has one limb 52 reciprocally mounted within the sleeve 46 and the other limb 53 projecting through the eye 50. An operating rod 54 engages the bend of the U-bolt, said operating rod being connected to a bell-crank lever 55, best shown in Figure 2^a, the free end 56 of which extends to a position adjacent one side of the handle bar 21. When the end 56 of the bell-crank lever is pushed inwardly longitudinal movement is transmitted to the U-bolt 51 through the rod 54. A spring 57 encircles the limb 53 of the U-bolt and is retained under compression between the eye 50 and the operating rod 54. By means of this spring the U-bolt remains normally retracted. The lifting pawl 43 is normally biased toward said ratchet wheel by the force of gravity acting through the weight 58, carried by an arm 59, and preferably forming part of the casting. The U-bolt 51 is out of the plane of the lifting pawl and ratchet wheel, and the limb 52 of said U-bolt lies in the plane of the cam 60.

Said cam is journaled upon the pin 17. The cam 60 is formed, on that portion which is designed to co-act with the limb 52 of the U-bolt, with shoulders of various heights having substantially radial walls. The shoulder 61 is the most elevated. Shoulders 62 and 63 are of substantially the same height, while shoulder 64 is the lowest. The number of shoulders is immaterial, and other shoulders than those shown may be provided without in any way transcending the scope of the invention. The shoulders define between them spaces into which the limb 52 of the U-bolt may descend and within which it may have ranges of movement of various lengths, the object of said spaces being to cause partial rotation of the cam 60 in a manner that will presently be described, for various lengths of stroke of the jack handle determined by the space available for movement of the jack handle.

The holding pawl 45 is preferably formed integral with a casting 65 which is pivotally mounted upon the pin 66. Said casting is provided, at one side of the holding pawl and in the plane of the cam 60, with a pair of keepers 67 and 68 lying on opposite sides

of the axis of the pin 66. The cam is provided on that side opposite the series of shoulders above mentioned, with a tubular extension 69, within which a plunger 70 slides, said plunger being normally urged outward by means of a spiral spring 71 within said tubular extension. The plunger normally rests within the keeper 68 but the cam is capable of a degree of rotation sufficient to cause the plunger to ride over the side of the pin 66 and to lodge in the other keeper 67. The pin 66 therefore serves as a detent to assist in retaining the plunger in one or the other of the keepers. In the normal position shown in Figure 1^b the plunger is in engagement with the keeper 68, the pressure of said plunger normally biasing the holding pawl into engagement with the ratchet wheel. It is obvious that when the cam is turned so that the plunger co-acts with the keeper 67 the pawl is biased in the opposite direction, that is to say, away from the ratchet wheel.

The casting 47 and its appurtenances including the U-bolt 51 perform two functions, namely setting the lifting pawl 53 alternately in operative or release positions, and throwing the cam 60 into normal (lifting) or release (lowering) positions. By way of illustration, the operation of the mechanism will now be traced beginning with the normal repose position of the jack handle shown in dotted lines in Figure 1. This is the position which the jack handle assumes, when let go, under the tension of the spring 39. As the jack handle flies up to this position, the end of the limb 52 of the U-bolt strikes the most elevated of the cam shoulders, 61, ensuring the oscillation of said cam, if it is in reverse position, back to normal position with the plunger 70 engaging the keeper 68. If the cam is already in normal position the shape of the keeper is such as to prevent the plunger from escaping therefrom and no movement of the cam takes place. In either event the casting 47 is swung in a counterclockwise direction so that the lifting pawl is raised to the release position. The extent of the counterclockwise swing of the casting 47 is limited by the arm 59 which is preferably bent so as to extend back of the jack handle and to engage the latter, the position of engagement being clearly shown at 72 in Figure 1^b. The advantage of this construction is that should the jack handle accidentally slip from the hand of the operator while a load is being lifted, said handle would automatically and instantly fly up and swing the cam 60 so as to place the holding pawl in a position to retain the load preventing the latter from falling with the jack. When the parts are in the dotted line position shown in Figure 1^b, the jack handle may be folded down above the main frame as shown in Figure 6 after pushing the end 56 of the bell-crank 130

lever outwardly a slight distance toward the end of the handle bar. This movement raises the lower end of the limb 52 of the U-bolt sufficiently to permit it to clear the end of the cam shoulder 61. The jack handle is provided adjacent its outer end with a projecting lug 73 adapted to rest in the middle of the lifting post which has not yet been described, and on the opposite side 10 of the jack handle is a similar protuberance 74 which strikes the ground when the jack handle is extended to the position shown in Figure 1^c, the purpose of which is to safeguard the operator from mashing his hand 15 between the jack handle and floor when operating close to a horizontal position.

Referring again to the dotted line position of the jack handle, shown in Figure 1^b and supposing that the operator wishes to 20 perform a lifting operation, he catches hold of the handle bar 21 with the full assurance that the holding pawl 45 has been automatically set for the lifting operation. In grasping the handle bar he avoids touching the 25 end 56 of the bell-crank lever. When he first begins to pull down on the jack handle, the end of the limb 52 of the U-bolt disengages from the shoulder 61. This permits gravity, acting through the weight 58 to 30 swing the U-bolt in a clockwise direction placing the lifting pawl 43 into engagement with the teeth 44 of the ratchet wheel. This disposition of parts is shown in full lines in Figure 1^b. The operator depresses the jack 35 handle through as great an arc as circumstances will permit, or a less arc if desired, the holding pawl 45 retaining whatever advance is made by the ratchet wheel. Nothing particularly novel happens on the 40 up stroke of the jack handle, in the lifting operation, the U-bolt remaining swung over in a clockwise direction and the lifting pawl merely riding back over the sloping surfaces of the ratchet teeth.

45 It will now be supposed that the operator wishes to lower the load. It is presumed by way of illustration that the handle is in the normal position of repose indicated by the dotted lines in Figure 1^b, but this will 50 not always be the case because automobiles vary in the amount of clearance beneath their axles, some being very low so that only a limited length of stroke is available. In such case the jack handle will be automatically lifted by the spring 39 to a position in which it collides with some part of the structure of the automobile which is being raised, and this will be its position at the beginning of the lowering operation. In 55 lowering the load the operator grasps the handle bar 21, pushes his fist against the end 56 of the bell-crank so as to depress the rod 54. This depresses the U-bolt 51 and compresses the spring 57. Compression of 60 said spring places a thrust against the arm

49, biasing the casting 47 in a counterclockwise direction so that the lifting pawl 43 will remain in release position when the end of the limb 52 of the U-bolt disengages from the cam shoulder 61. This position is indicated in dotted lines in Figure 3. The simultaneous depression of the end of the limb 52 places said end within one of the recesses formed between the shoulders upon the arm 60, and the operator by moving the 70 end 56 of the bell crank more or less inwardly toward the center of the handle bar determines which of the recesses said end shall enter. For instance, if he has available but a small range of movement for the 75 jack handle whether the latter be in a substantially vertical position as when working close to a wall or in a limited position near the horizontal as when working under a low hung axle, he pushes the end of the limb 52 of the U-bolt in as far as it will go. Should he be working with the jack handle near the vertical, the position of the parts before depression of the U-bolt will be that shown in dotted lines in Figure 1^b. When the U-bolt 80 is depressed the end of the limb 52 will play within the recess between the cam shoulder 61 and the cam shoulder 62. After having depressed the U-bolt into said recess the operator pushes down upon the jack handle. 85 This causes the end of the limb 52 to strike against the left hand side of the cam shoulder 62 as viewed from Figure 1^b. Two results follow, one is the oscillation of the cam 90 60 in a clockwise direction throwing the plunger 70 over into the keeper 67. This action is not sufficient of itself to throw the holding pawl into inoperative position because the load is bearing down with great frictional pressure against the nose of the pawl 45, holding it in opposition to the releasing tendency of the plunger 70. The other result is the swinging of the casting 47 in a clockwise direction against the tension 95 of the spring 57. This throws the lifting pawl 100 into operative position. As the operator bears down upon the jack handle, the lifting pawl takes the load away from the holding pawl permitting the latter to fly out into inoperative position under pressure of the plunger 70. The operator then lets the jack handle rise under the pressure of the descending load and as soon as the end of the limb 52 of the U-bolt again strikes the shoulder 61 of the cam 60 said cam will be 105 oscillated in a counter-clockwise direction to throw the plunger into the keeper 68, the holding pawl 45 being thereby again placed into operative position. As soon as the load 110 has been taken up by the holding pawl the lifting pawl again flies out under the pressure of the spring 57.

115 It will be understood that the operator maintains the outer end 56 of the bell-crank 120 55 in depressed position during the entire 125 130

icad lowering movement of the jack and that he does not have to change the position of his hand during that movement.

If the jack handle can only be manipulated within a narrow range of movement near the horizontal, the end of the limb 52 will play within the deep recess between the cams 62 and 64, as shown in full lines in Figure 3. Should a greater range of movement of the jack handle be practicable, the operator will not have to depress the end of the U-bolt quite so far. It may then operate between the cam shoulders 62 and 63, passing over the shoulder 64. Should there be room for a full stroke of the jack the operator will press the U-bolt in but a very slight distance so that the end of the limb 52 will travel between the cam shoulders 61 and 63. As has been hereinbefore stated, the particular disposition of cam shoulders and the length of the several recesses which they define is purely illustrative and is not intended to impose a limitation upon the invention.

The ratchet wheel 41 is limited in its movement in either direction by means of a boss 75 which projects from one side of said ratchet wheel and is engageable with opposite sides of the tubular extension of the cam 60. The object of this boss is to prevent excessive elevation of the canti-lever which might otherwise permit the wedge 27 to pass entirely through between the rollers 31 and 34, causing the load to crash. When the extreme limit of ascent of the canti-lever has been reached the boss 75 comes around and strikes the tubular extension on the under side, throwing the cam 60 to reverse position so that further attempt to lift the load will result in the holding pawl flying out so that no further elevation of the canti-lever will be sustained. Conversely, in order to prevent the canti-lever being lowered too far within the main frame the boss 75 will strike the upper end of the tubular extension while the cam 60 is in reverse position during the load lowering operation, throwing the plunger 70 over the normal position and causing the holding pawl to assume its operative position, preventing further descent of the load. Contact of the boss 75 with the tubular extension either at the upper or lower limit of the range of movement of the lifting mechanism reacts upon the ratchet wheel, inhibiting its further rotation and leaving it in proper position for the return movements of the lifting means. This eliminates the possibility of throwing an excessive strain upon the lifting mechanism beyond the ratchet wheel when the jack has reached its highest point, and prevents the chain from sagging and dragging the ground when the lifting mechanism is at its lowest point. The lower end 55 of the tubular extension 69 is formed with

a nose 76 with which the keeper 68 makes contact when the holding pawl moves to release position, preventing the holding pawl from moving out an excessive distance, or

70

The canti-lever 22 is provided at its outer end with a lifting post 77 which is preferably hollow and conforms to the shape of the closed end of the canti-lever, being slidable relative thereto. The lifting post is provided on its forward face with ratchet teeth 77^a having the abrupt shoulders thereof downwardly directed and engagable with a pawl 78 consisting preferably of a piece of strap iron having a flat portion extending transversely of the canti-lever, and angularly bent portions extending downwardly at each side of the canti-lever and being pivoted thereto by means of the bolt 79. An operating arm 80 is secured in any suitable manner to one side of the pawl 78 and is normally biased in an upward direction by means of a spring 81 so that the transverse portion of the pawl 78 makes contact with the teeth carrying face of the lifting post. The bottom of the lifting post may be furnished with lugs 82 extending downwardly and engageable with the lower edges of the canti-lever to limit the upward extension of the lifting post. A load supporting platform 83 is swivelly carried upon the top of the lifting post.

75

The object of the pawl 78 and ratchet teeth 77^a is to enable the operator of the jack to make a preliminary rough setting of the same at approximately the desired height to permit the jack to be slipped under the load. This he does prior to the placing of the jack by simply raising the platform 83 by hand, the ratchet teeth slipping past the pawl 78. To lower the lifting post the operator merely places his foot upon the operating bar 80, depressing the same against the tension of the spring 81, this pulls the pawl 78 away from the ratchet teeth and the post drops. The preliminary elevation of the post and its descent are always accomplished before placing the jack beneath the work.

80

One of the disadvantages attending the use of a wheeled jack is the ease with which it slips about from under the work while the jack handle is being manipulated in the lifting operation preparatory to the moment when the jack takes hold of the work. This is avoided in the present invention by the use of auxiliary ratchet operating means consisting of an operating rod 84 having one end thereof conveniently adjacent the handle bar and the other end formed with a ratchet-wheel-tooth engaging portion 85. Said operating rod is normally biased away from the ratchet wheel by means of the spiral spring 86 arranged in compression between a collar 87 on the operating rod and

85

an eye 88 on the jack handle. Said eye surrounds the operating rod and has an aperture 89 of larger size than said operating rod so as to provide lost motion in order to 5 permit the operating rod to move downwardly relative to the handle of said jack so as to follow the ratchet teeth around from the point at which it first makes contact with the ratchet wheel to the point of substantial tendency thereto. The auxiliary ratchet wheel operating mechanism is worked up and down to rotate the ratchet wheel in a canti-lever-raising direction.

It will be understood that there are three 15 distinct elevating means for the jack, first the lifting post which is directly elevated by hand, second the auxiliary ratchet wheel operating mechanism which is operated while the jack is beneath the automobile the 20 jack handle being firmly held, at the same time, to prevent the jack being displaced relative to the work, and finally the main jack elevating mechanism which is operated by working the jack handle back and forth 25 in a well understood manner.

Referring now to the jack as a whole, it will be noted from Figure 6 that the main frame 1 inclines downwardly from the end 30 adjacent the caster 14 to the end adjacent the vehicle wheels, and that the canti-lever 22 is pivoted to the main frame at an intermediate point. That portion of the canti-lever adjacent its pivotal connection with the main frame slopes slightly upward, the 35 result of this construction being that the lowest point on the entire jack is adjacent said pivotal connection. It is preferred to make the actual length of the canti-lever, from the center of the platform 83 to the 40 pivot pin 23 equal to one-half the width of tread of an auto vehicle, that is to say 28 inches. This makes it possible to place the platform 83 beneath the middle of the front or rear axle by elevating the axle just 45 sufficiently to permit the wheels to clear the ground by a distance of equal to the elevation of the low point of the jack, and to swing the jack around to a position at right angles to its original position upon the axis 50 of the platform 83 as a center beneath one of the elevated wheels of the auto vehicle. In this manner it is possible, with a minimum amount of lifting to make almost any 55 desired manoeuvre with the automobile in a limited space. It will be observed that the free end of the canti-lever inclines downward sufficiently to bring the platform 83 just below the level of the top of the wheels 60 5 and 6 making it possible for the jack to be operated in any space through which the vehicle wheels can pass.

The chain 37 which winds around the ratchet wheel drum 38 is of novel construction, being designed to oppose as little frictional resistance as possible to the opera-

tion of the jack. This is done not only with the idea of making it materially easier to lift the load but to ensure the return of the wedge 25 by gravity to its normal inoperative position. The chain is constructed of 70 pins 90 connected by side links 91. Said side links are made larger at one end than the other and are so arranged that the large end of one link and the small end of the successive link are journaled upon the same 75 pin. The result of this is that instead of both links bearing upon the drum as the chain is wound therearound the edge of only the large end of the link will bear upon said drum, the small end being maintained out 80 of contact therewith. The rod 35 passes above the pin 23 and spacing sleeve 24. In order to assist in a comparatively frictionless return of the wedge to its normal position, a loose sleeve 92 surrounds said spacing sleeve 85 against which the rod 35 rests when the chain 37 becomes slack.

Having now described an illustrative embodiment of the principles of my invention, it is to be understood that my invention is 90 not limited to the precise details of construction shown, but that it is entitled to as broad an interpretation as is permitted by the state of the prior art.

Having described my invention what I 95 claim as new and desire to secure by Letters Patent, is:

1. A lifting jack comprising a main frame including spaced longitudinal members, a canti-lever extending lengthwise of said frame, load supporting means carried solely by said canti-lever adjacent the free end thereof, the other end of said canti-lever being pivotally connected to said frame below the plane which embraces the upper 100 sides of said longitudinal members, and means carried by said frame and engaging an intermediate portion of said canti-lever for elevating the free end of said canti-lever.

2. A lifting jack including a main frame, a canti-lever pivotally connected to said main frame, a wedge forcible between an element of said cantilever and an element of said main frame for elevating said cantilever, and means for moving said wedge in 115 a direction to elevate said cantilever.

3. A lifting jack including a main frame, a canti-lever pivotally connected to said main frame, a load-supporting platform carried by said canti-lever, rollers carried in 120 juxtaposition by said canti-lever and said main frame, a wedge forcible between said rollers for elevating said canti-lever, and means for moving said wedge in a direction 125 to elevate said canti-lever.

4. A lifting jack including a main frame, a canti-lever pivotally connected to said main frame, a load-supporting platform carried by said canti-lever, rollers mounted in juxtaposition upon said frame and canti-lever,

5. A wedge forcible between said rollers for elevating said canti-lever, and independent means for elevating said load-supporting platform and for moving said wedge in a direction to raise said canti-lever.
6. A lifting jack including lifting means, a ratchet wheel operatively connected to said lifting means, an operating lever, a lifting pawl actuated by said lever and co-acting with the ratchet wheel, a holding pawl also co-acting with said ratchet wheel, an oscillatable cam having a portion engaging said pawl to throw it into or out of operative position, and means on said lever, for oscillating said cam in any one of a number of selective positions of said lever.
7. A lifting jack including lifting means, a ratchet wheel operatively connected to said lifting means, an operating lever, a lifting pawl actuated by said lever and co-acting with the ratchet wheel, a holding pawl also co-acting with said ratchet wheel, an oscillatable cam having a portion engaging said pawl to throw it into or out of operative position, and means on said lever for oscillating said cam in any one of a number of selective positions of said lever, said means being operably connected to said lifting pawl to throw the latter into or out of operative position in certain positions of said lever.
8. A lifting jack including lifting means, a ratchet wheel operatively connected to said lifting means, an operating lever, a lifting pawl actuated by said lever and co-acting with the ratchet wheel, a holding pawl also co-acting with said ratchet wheel, an oscillatable cam having a portion engaging said pawl to throw the latter into or out of operative position and means for oscillating said cam in any one of a number of selective positions of said lever, said means being operably connected to said lifting pawl to throw the latter into and out of operative position in certain positions of said lever.
9. A lifting jack including lifting means, a ratchet wheel operatively connected to said lifting means, an operating lever, a lifting pawl actuated by said lever and co-acting with the ratchet wheel, a holding pawl also co-acting with said ratchet wheel, an oscillatable cam having a portion engaging said pawl to throw the latter into or out of operative position, means movable with said lever for oscillating said cam in any one of a number of selective positions of said lever, said cam being provided with a shoulder engageable with said means when said lever is placed in a certain position for oscillating said cam to place said holding pawl in operative position.
10. A lifting jack including lifting means, a ratchet wheel operatively connected to said lifting means, an operating lever, a lifting pawl actuated by said lever and co-acting with the ratchet wheel, a holding pawl also co-acting with said ratchet wheel, an oscillatable cam having a portion engaging said pawl to throw it into or out of operative position, and means on said lever, for oscillating said cam in any one of a number of selective positions of said lever.
11. A lifting jack including lifting means, a ratchet wheel operatively connected to said lifting means, an operating lever, a lifting pawl actuated by said lever and co-acting with the ratchet wheel, a holding pawl also co-acting with said ratchet wheel, a pivotedly supported holding pawl also co-acting with said ratchet wheel, said holding pawl being provided with keepers on opposite sides of its pivotal axis, an oscillatable cam having a tubular portion directed toward said keepers, an outwardly spring-pressed plunger within said tubular portion, said plunger shifting from one keeper to the other as the cam is oscillated to throw said holding pawl into or out of operative position, and means movable with said lever for oscillating said cam in any one of a number of selective positions of said lever.
12. A lifting jack including lifting means, a ratchet wheel operatively connected to said lifting means, an operating lever, a lifting pawl actuated by said lever and co-acting with the ratchet wheel, a holding pawl also co-acting with said ratchet wheel, said holding pawl being provided with keepers on opposite sides of its pivotal axis, an oscillatable cam having a tubular portion directed toward said keepers, an outwardly spring-pressed plunger within said tubular portion, said plunger shifting from one keeper to the other as the cam is oscillated to throw said holding pawl into or out of operative position, and means movable with said lever for oscillating said cam in any one of a number of selective positions of said lever.
13. A lifting jack including lifting means, a ratchet wheel operatively connected to said lifting means, an operating lever, a lifting pawl actuated by said lever and co-acting with the ratchet wheel, a holding pawl also co-acting with said ratchet wheel, a pivotedly supported holding pawl also co-acting with said ratchet wheel, said holding pawl being provided with keepers on opposite sides of its pivotal axis, an oscillatable cam having a tubular portion directed toward said keepers, an outwardly spring-pressed plunger within said tubular portion, said plunger shifting from one keeper to the other as the cam is oscillated to throw said holding pawl into or out of operative position, and means movable with said lever for oscillating said cam in any one of a number of selective positions of said lever.

5 said tubular extension, said plunger shifting from one keeper to the other as the cam is oscillated to throw said holding pawl into or out of operative position, and means movable with said lever for oscillating said cam in any one of a number of selective positions of said lever, said cam being provided with a shoulder engagable with said means when said lever is placed in a certain 10 position, for oscillating said cam to place said holding pawl in operative position.

13. A lifting jack including lifting means, a ratchet wheel operatively connected to said lifting means, an operative lever, a lifting pawl actuated by said lever co-acting with the ratchet wheel, a pivotally supported holding pawl also co-acting with said ratchet wheel, said holding pawl being provided with keepers on opposite sides of its 20 pivotal axis, an oscillatable cam having a tubular portion directed toward said keepers, an outwardly spring-pressed plunger within said tubular extension, said plunger shifting from one keeper to the other as said cam is oscillated to throw said holding pawl into or out of operative position, means movable within said lever for oscillating said cam in any one of a number of selective positions of said lever, means for 30 automatically raising said lever to a normal position of repose, said cam being provided with a shoulder engagable with said movable means when said lever is raised for oscillating said cam to place said holding pawl in operative position and retaining it in that position while said lever is in position of repose.

14. A lifting pawl including lifting means, a ratchet wheel operatively connected to said lifting means, an operating lever, a lifting pawl actuated by said lever co-acting with the ratchet wheel, a pivotally supported holding pawl also co-acting with said ratchet wheel, said holding pawl being 45 provided with keepers on opposite sides of its pivotal axis, an oscillatable cam having a tubular portion directed toward said keepers, an outwardly spring-pressed plunger within said tubular extension, said plunger shifting from one keeper to the other as the cam is oscillated to throw said holding pawl into or out of operative position, said tubular portion being formed with a nose contacting with the opposite keeper when the 55 spring-pressed plunger is in co-action with the keeper holding the pawl in inoperative position, to prevent overturning of said pawl.

15. A lifting jack including a lifting means, a ratchet wheel for operating said lifting means, a holding pawl co-acting with said ratchet wheel, means for reversing said holding pawl to move it into and out of operative position, an operating lever for said ratchet wheel, means carried by said

lever for actuating said reversing means, a lifting pawl carried by said lever, means for simultaneously bringing said actuating means into engagement with said reversing means and moving said lifting pawl to its 70 inoperative position, said actuating means, reversing means and lifting pawl being so constructed that the re-action of said reversing means, when reversed, is transmitted through said actuating means to cause the 75 return of said lifting pawl to operative position.

16. A lifting jack including lifting means, a ratchet wheel for operating said lifting means, a holding pawl co-acting with said ratchet wheel, means for reversing said pawl to move it into and out of operative position, an operating lever for said ratchet wheel, means carried by said lever for actuating said reversing means in any one of 80 a number of selective positions of said lever, a lifting pawl carried by said lever, means for simultaneously bringing said actuating means into engagement with said reversing means, and moving said lifting pawl into inoperative position, said actuating means, reversing means, and lifting pawl being so constructed that the re-action of said reversing means, when reversed, is transmitted through said actuating means to cause the 85 return of said lifting pawl to operative position.

17. A lifting jack comprising a frame, lifting means carried by said frame, a ratchet wheel operatively connected to said lifting means and an operating lever therefor, a member pivotally mounted on said lever, a lifting pawl carried by said member and co-acting with said ratchet wheel, a holding pawl pivotally mounted on said 100 frame provided with keepers on opposite sides of its pivotal axis, pivotally mounted reversing means for said holding pawl including a spring-pressed plunger engageable with either of said keepers when said reversing means is oscillated, said reversing means being formed with recesses defining shoulders, actuating means for said reversing means including a reciprocable member carried by said pivotally mounted member and engageable with certain of said recesses in 105 selective positions of said lever, a spring connecting said reciprocable member to said pivotally mounted member at one side of the pivotal axis of the latter, means for depressing said reciprocable member to cause it to enter one of said recesses and simultaneously to compress said spring, thereby biasing said pivotally mounted member in 110 a direction to move said lifting pawl to inoperative position, said spring being of less pressure than the resistance of said reversing means to movement when said reciprocable means engages a shoulder thereof 115 to enter one of said recesses and simultaneously to compress said spring, thereby biasing said pivotally mounted member in a direction to move said lifting pawl to 120 inoperative position, said spring being of less pressure than the resistance of said reversing means to movement when said reciprocable means engages a shoulder thereof 125 to enter one of said recesses and simultaneously to compress said spring, thereby biasing said pivotally mounted member in a direction to move said lifting pawl to 130 inoperative position, said spring being of less pressure than the resistance of said reversing means to movement when said reciprocable means engages a shoulder thereof

- means so as to move said holding pawl to inoperative position, the pivotally mounted member being thereby biased in a direction to throw said lifting pawl back into operative position simultaneously with the movement of said holding pawl to inoperative position. 18. A lifting jack comprising a frame, lifting means carried by said frame, a ratchet wheel operatively connected to said lifting means and an operating lever therefore, a member pivotally mounted on said lever, a lifting pawl carried by said member and co-acting with said ratchet wheel, a holding pawl pivotally mounted on said frame provided with keepers on opposite sides of its pivotal axis, pivotally mounted reversing means for said holding pawl including a spring-pressed plunger engageable with either of said keepers when said reversing means is oscillated, the pressure of said plunger being insufficient to move said holding pawl to inoperative position until it is relieved from the frictional resistance of the load imposed upon it by said ratchet wheel, through a slight lifting movement of said operating lever, said reversing means being formed with recesses defining shoulders, actuating means for said reversing means including a reciprocable member carried by said pivotally mounted member and engagable with certain of said recesses in selective positions of said lever, a spring connecting said reciprocable member to said pivotally mounted member at one side of the pivotal axis of the latter, means for depressing said reciprocable member to cause the same to enter one of said recesses and simultaneously to compress said spring, thereby biasing said pivotally mounted member in a direction to move said lifting pawl to inoperative position, said spring being of less pressure than the resistance to movement of said reversing means so that when said reciprocable means engages a shoulder of said reversing means to oscillate the latter to cause it to move said holding pawl to inoperative position, the pivotally mounted member is thereby biased in a direction to throw said lifting pawl back into operative position simultaneously with the movement of said holding pawl to inoperative position. 19. A lifting jack comprising a frame, lifting means carried by said frame, a drum rotatably mounted in said frame, a ratchet wheel fixed relatively to said drum, flexible means windable upon said drum for elevating said lifting means, an operating lever, a member pivotally mounted on said lever, a lifting pawl carried by said member and co-acting with said ratchet wheel, a holding pawl pivotally carried by said frame and provided with keepers on opposite sides of its pivotal axis, a cam oscillatably mounted co-axially with said ratchet wheel, said cam including a spring-pressed plunger engageable with either of said keepers when said cam is oscillated, said cam being formed with recesses defining shoulders, and actuating means for said cam including a reciprocable member carried by said pivotally mounted member and engageable with certain of said recesses in selective positions of said lever. 20. A lifting jack comprising a frame, lifting means carried by said frame, a drum rotatably mounted in said frame, a ratchet wheel fixed relative to said drum, flexible means windable upon said drum for elevating said lifting means, an operating lever, a member pivotally mounted on said lever, a lifting pawl carried by said member and co-acting with said ratchet wheel, a holding pawl pivotally carried by said frame and provided with keepers on opposite sides of its pivotal axis, a cam oscillatably mounted co-axially with said ratchet wheel, said cam including a spring-pressed plunger engageable with either of said keepers when said cam is oscillated, said cam being formed with recesses defining shoulders, actuating means for said cam including a reciprocable member carried by said pivotally mounted member and engageable with certain of said recesses in selective positions of said lever, a spring connecting said reciprocable member to said pivotally mounted member at one side of the pivotal axis of the latter, and means for depressing said reciprocable member to cause the same to enter one of said recesses and simultaneously to compress said spring, thereby biasing said pivotally mounted member in a direction to move the lifting pawl to inoperative position. 21. A lifting jack including lifting means, a ratchet wheel operatively connected to said lifting means, an operating lever, a lifting pawl actuated by said lever and co-acting with the ratchet wheel, a holding pawl also co-acting with said ratchet wheel, an oscillatable cam having a portion engaging said pawl to throw the latter into or out of operative position, and another portion formed with recesses defining shoulders, actuating means for said cam including a reciprocable member carried by said lifting pawl engageable with certain recesses in selective positions of said lever, means for automatically raising said lever to a normal position of repose, said cam being provided with a shoulder engageable with said reciprocable member when said lever is raised, for oscillating said cam to place the holding pawl in operative position and retaining it in that position while said lever is in position of repose, the engagement of said reciprocable member with said shoulder moving said lifting pawl to an inoperative position, said lifting pawl and reciprocable member be-

- ing normally overbalanced to restore said lifting pawl to operative position by gravity when said reciprocable member is disengaged from said shoulder by descent of said lever. 5
22. A lifting jack including lifting means, a ratchet wheel operatively connected to said lifting means, a holding pawl co-acting with said ratchet wheel and means movable with 10 said ratchet wheel for throwing said pawl into or out of operative position with respect to said ratchet wheel at the respective low and high limits of the range of movement of said lifting means. 15
23. A lifting jack including lifting means, a ratchet wheel operatively connected to said lifting means, an operating lever, a lifting pawl actuated by said lever co-acting with the ratchet wheel, a pivotally supported 20 holding pawl also co-acting with said ratchet wheel, said pawl being provided with keepers on opposite sides of its pivotal axis, an oscillatable cam having a tubular portion directed toward said keepers, an outwardly 25 spring-pressed plunger within said tubular portion, said plunger being adapted to shift from one keeper to the other as the cam is oscillated to throw said holding pawl into or out of operative position, means movable 30 with said lever for oscillating said cam in any one of a number of selective positions of said lever and means on said ratchet wheel engageable with said tubular portion on opposite sides thereof for shifting said pawl at 35 extreme high and low ranges of movement of said lifting means. 40
24. A lifting jack including lifting means, a ratchet wheel operatively connected to said lifting means, an operating lever, a lifting pawl actuated by said lever co-acting with said ratchet wheel and an auxiliary lifting pawl operable independently of said lever. 45
25. A lifting jack including a frame, a canti-lever pivotally connected thereto, a drum pivotally mounted upon said frame and having a ratchet wheel fixed thereto, means for operating said ratchet wheel, and a connection between said lifting means 50 and drum including a flexible chain formed of pins connected by links, the juxtaposed ends of adjacent links being journaled upon the same pin, the distance from said pin to the lower end of one of said juxtaposed ends being greater than the distance from 55 said pin to the lower edge of the other, whereby but one of said ends makes frictional engagement with said drum when the ratchet wheel is operated. 60
26. A lifting jack including a main frame, independently rotatable vehicle wheels adjacent one end of the frame and a 65 caster adjacent the other end, said frame inclining downwardly from the end adjacent the caster to the opposite end, a canti-lever pivotally connected to said main frame at an intermediate point, and means for elevating said canti-lever. 70
27. A lifting jack including a main frame and a supporting axle therefor, a canti-lever pivotally connected to said main frame, a platform carried by said canti-lever adjacent said axle and means engaging said canti-lever and movable rectilinearly for elevating said canti-lever. 75
28. A lifting jack including lifting means, a ratchet wheel operatively connected to said lifting means, a holding pawl co-acting with said ratchet wheel, and means movable with said ratchet wheel for throwing said pawl into or out of operative 80 position with respect to said ratchet wheel, and for stopping the movement of said ratchet wheel, at the respective low and high limits of the range of movement of 85 said lifting means. 90
29. A lifting jack including lifting means, a ratchet wheel operatively connected to said lifting means, and means movable with said ratchet wheel and engageable with another part of said jack mechanism for preventing further rotation of said ratchet wheel at the respective low and high limits of the range of movement of said lifting means. 95

In testimony whereof I have hereunto set my hand.

ERNEST W. HOLMES.
